PORTABLE RIVET HEATER

Louis C. Guertin, Worcester, Mass.

Application December 4, 1942, Serial No. 467,845

10 Claims. (Cl. 263—9)

This invention relates to portable rivet heaters which are easily carried from one place to another so that riveters may have the heated rivets conveniently at hand.

Objects of the invention include the provision of a small but efficient portable rivet heater having a refractory brick lining, there being a rivet holder in the furnace for supporting rivets in a compact condition, and an oil burner which is mounted outside of the furnace but which is portable therewith; the provision of a portable rivet heater as aforesaid including a pivoted platform support for the oil burning unit, said support being mounted on the frame of the heater and being adapted for pivoting between the folded inoperative position and an extended operative position for further convenience in the portability and storage of the device; and the provision of a portable rivet heater as aforesaid including a flexible support for a free edge of the oil burner platform, and a weather protector therefor, said weather protector being supported on the flexible platform support.

Further objects of the invention include the provision of a portable rivet heater embodying a refractory bricklined furnace, a grate having bars which are spaced to permit the shanks of the rivets to depend therefrom, the heads of the rivets being supported on the bars, a separate oil burning unit which is positioned to deliver a flame through a wall of the furnace at any desired point below the grate bars for uniformity in heat, there being a wedge shaped space take-up being positioned between one lateral side of the grate and the furnace wall so as to prevent loss of heat, and there also being a pair of cover plates to be disposed on the rivet heads so as to maintain the heat under either of the cover plates while the other is removed to provide access to the rivets.

Other objects and advantages of the invention will appear hereinafter.

Reference is to be had to the accompanying drawings in which

Fig. 1 is a plan view of an embodiment of my new rivet heater with the weather protector removed;

Fig. 2 is a view in side elevation of the rivet heater with parts in section and looking in the direction of arrow 2 in Fig. 1;

Fig. 3 is a section on line 3—3 of Fig. 2 with the weather protector omitted;

Fig. 4 is a partial plan view of the grate and showing the cover plates;

Fig. 5 is a view in side elevation of Fig. 4;

Fig. 6 is an enlarged view of the grate take-up; Fig. 7 is an enlarged view of the oil burner nozzle, parts being in section; and

Fig. 8 is a bottom plan view of the weather protector.

As seen in Figs. 1 and 2, my new rivet heater comprises a framework composed of a bottom member 10, longitudinal side members 12 and end members 14. This framework is provided with 10 a plurality of legs 16 which as shown are in the form of angle irons which may be secured to the framework in any desired manner. These legs extend below the bottom member 10 and space the latter from a floor line as at 18 in Fig. 2. 15 The bottom member 10 is overlaid by and supports a bottom refractory brick lining 20, and the sides and ends of the framework are lined by similar bricks as at 22. A pair of handles 24 may be attached to the framework ends or side members for carrying the entire furnace from point to point on the job.

In the present embodiment of the invention I disclose a grate which is composed of side members 26 and end members 28, there being a plurality, in this case three for illustration, of grate bars 30 which extend longitudinally of the grate in spaced relation to the side members 26. The side members 26 and bars 30 are spaced to accommodate the rivet shanks or rivets being heated, the bars being spaced a distance just sufficient to keep or maintain the rivets by their heads as shown in 32. It will be seen that this grate will accommodate a large number of rivets in a manner so that the rivet shanks depend below the grate. In the illustration I have disclosed three legs 34 at each end of the grate and legs 36 on each grate bar and on the side elements 26, these legs being located at both sides of the center 38 of the grate as shown in Fig. 1, leaving 35 the center of the grate free and unimpeded to receive a flame through the center aperture 40 in a side of the furnace below the grate. Thus it will be seen that the flame will enter the furnace below the grate, see Fig. 2, and not directly strike 40 any of the metal of the grate.

I provide a pair of cover elements 42, each one of which is adapted to cover one half of the grate area, and I provide apertures 44 through these plates so that they may be removed and replaced 50 by means of tongs. Plates 42 will over-lie the rivet heads and will maintain the heated atmosphere below the same so that all the rivets will receive substantially the same uniform amount of heat, and one cover plate may be removed so 55 that some of the rivets in the heater may be

removed while other rivets are still covered. I also provide a wedge shaped space take-up 46 which is to be inserted as shown in Fig. 2 between the rear wall of the furnace and the adjacent grate element 26 so as to prevent loss of heat and escape of flame at the rear side of the grate while providing for easy removability of the grate in cases where a grate having bars of different spacing for different sized rivets is desired to be used in place of the grate shown. This space take-up member is provided with a handle 48.

A supporting platform 50 is pivoted as by a hinge 52 to a member of the framework, so that this platform may be extended as shown in Figs. 1 and 2 at right angles to the heater for supporting an oil burner unit 54, or selectively the platform may be pivoted into parallel relation with the adjacent side of the furnace for ease in portability and compact storage of the entire unit. I provide an aperture 56 in the platform 50 for reception of a screw 58 attached to the bottom of the oil burner unit 54, there being a washer 60 bridging the aperture and used to hold the oil burner unit in correctly positioned location thereon for the best flame in the furnace.

The oil burner itself comprises a wick box 62 in which is mounted an oil pipe 64 leading from a source of oil not shown and extending forwardly to the left in Fig. 2 where it is coiled a plurality of times at 66 to provide a fire chamber. Oil pipe 64 is reversed at the forward end of the burner and as shown in Fig. 2 a depending end pipe 68 is provided to which is attached a nozzle 70 in a cap 72 which is screw threaded to the end of the pipe as shown in Fig. 7. The nozzle itself comprises an elongated element which is screw threaded into cap 72 in the manner shown in Fig. 7, and this element is provided with a longitudinal passageway 74 forming the nozzle for the oil. Screw thread 76 on the element 70 provides a dirt catching means for the oil flowing through pipe 68. The irregular surface provided by the screw threads in reality forms a trap in which dirt particles in the flowing oil will be received.

A pair of chains 78 are suspended from hooks 80 and these chains pass into slots 82 in the platform 50 so that the free end of the platform is supported by the chains, slots 82 being narrower than the width of the links in the chain. Adjacent hooks 80, the chains are provided with depending hooks 84 in which are received bent fingers 86 in a plate 88. By this means plate 88 is supported on the chains and extends downwardly therewith to form a removable weather protector for the oil burner.

It is to be understood that the aperture 40 through the brick wall of the furnace may be located in any desired position other than that shown. For instance it might be located in either end of the furnace or in the side walls more adjacent the ends. Several of these apertures could be used so that the oil burner could be located where desired so as to heat the interior of the furnace to any desired point, or several burners may be used at once.

It will be seen from the above that I have provided a very efficient and portable rivet heater which may be easily carried about to be located wherever the riveter is working, and therefore the present invention will save time on any job; and in addition will ensure a more

even and uniform heating of the rivets. A cover may be provided for the heater if desired and it will be clear that such cover can assume any desired form.

Having thus described my invention and the advantages thereof, I do not wish to be limited to the details herein disclosed, otherwise than as set forth in the claims, but what I claim is:

1. A rivet heater comprising a furnace, a grate in said furnace including spaced bars and means to support the bars above the bottom of the furnace, oil burning means to heat the furnace, and a plurality of separate cover members for disposition over rivets supported on the bars, each cover member being of lesser area than the area of the furnace, and each cover being separately removable to expose a portion only of the rivets.

2. A rivet heater comprising a furnace, a pivoted platform supported on the furnace exteriorly thereof, an oil burner adapted to be mounted on the platform, and an aperture through a wall of the furnace for admission of the oil burner flame into the furnace.

3. A rivet heater as recited in claim 2 wherein the oil burner is removable from the platform, and the latter is selectively pivotable between positions wherein it is at right angles to a wall of the furnace or parallel thereto.

4. A rivet heater as recited in claim 2 including flexible means anchored to a wall of the furnace and extending to a free edge of the platform to support the latter at right angles to the furnace wall aforesaid.

5. A rivet heater as recited in claim 2 including means for adjustably detachably securing the oil burner to the platform.

6. A rivet heater as recited in claim 2 wherein the oil burner comprises an oil line infeed pipe which is coiled a plurality of times and reversed, and a nozzle for directing flame through the coils into the furnace.

7. A portable rivet heater comprising a furnace, an exterior platform pivoted at an edge thereof to a wall of the furnace, an oil burner on the platform, flexible means secured to a free edge of the platform and to the wall to support the platform, and a weather protector for the oil burner detachably mounted on said flexible means.

8. A portable rivet heater as recited in claim 7 wherein said flexible means comprises a chain, there being a hook on the chain, and a depending finger on the weather protector engaged in the hook.

9. A portable rivet heater as recited in claim 7 wherein said flexible means includes a hook and said weather protector is in the form of a flat sheet having a depending finger engaged in the hook, said sheet resting on the flexible means.

10. A portable rivet heater comprising a brick lined furnace of a size and weight capable of manual portability; a fire aperture in said furnace, an oil burner mounted exteriorly of the furnace and positioned to project flame through the aperture, a grate in said furnace for supporting rivets, the rivet supporting portion of the grate being located in a horizontal plane above the fire aperture, said grate being removable from the furnace, and a wedge shaped bar for insertion between an edge of the grate and a wall of the furnace to plug any open space at that point.

LOUIS C. GUERTIN.
